UNITED STATES PATENT OFFICE.

ANNIE L. WORTHLEY, OF LOS ANGELES, CALIFORNIA.

BEDCLOTHES-HOLDER.

1,092,468.

Specification of Letters Patent.

Patented Apr. 7, 1914.

Application filed January 29, 1913. Serial No. 744,877.

To all whom it may concern:

Be it known that I, ANNIE L. WORTHLEY, a citizen of the United States, residing in the city of Los Angeles, county of Los Angeles, State of California, have invented 5 a new and useful Improvement in Bed-clothes-Holders, of which the following is a specification.

This invention relates to bed clothes 10 holders, and particularly to bed clothes holders adapted to secure the bed clothes transversely of the bed after an occupant has been placed therein, and the principal object is to provide a holder that is quickly 15 secured to the side rail of the bed and clamps the clothes to the upright rod connected therewith.

It is a further object to provide two 20 members composing the holder of wire of light weight and sufficient resiliency to engage the bed rail and lock the rail engaging member, together with the bed clothes in contact with the desired upright rod of the side of a bed.

25 In the drawings, Figure 1 is a perspective view of a bed, showing the invention applied thereto. Fig. 2 is an enlarged elevation of the rail engaging member viewed from the inner side of the rail to which it is 30 engaged. Fig. 3 is an end elevation of the same member, showing the bed clothes and the clamp member in dotted lines, together with a section of rod and lower rail. Fig. 35 4 is a plan view of the upper portion of the rail engaging member, the rod being shown in section and the clamp member in dotted lines. Fig. 5 is a plan view of the clamp member, showing the bed rod in section.

This invention is particularly applicable 40 for use in children's beds and especially where children are prone to throw off the bed clothes after once being placed in position, and the invention, as shown, is applied to such a child's bed, although it may 45 be adapted to a number of similar uses, the main portion of the holder consisting of the rail engaging member 7, which is preferably formed of an integral piece of wire sufficiently stiff to retain the required shape and 50 sufficiently resilient to permit of enough elasticity to slide the loop 8 forming the ends of the wire, over the lower rail 9, forming, together with the top rail 10 and intermediate rod 11, a side of the common metallic child's bed.

The loop 8 is preferably formed of the

configuration shown, having its opening facing the inner side of the rail, the wire being further bent to form the limb 12 of a yoke having a horizontal portion 14, this horizontal portion being again bent to form the substantially vertical shank 15, above which a loop 16 is formed extending in the opposite direction from the loop 8, the wire being again bent to form loop 17 in the same direction as the loop 8, and again bent back to form the loop 18, extending slightly beyond the loop 16 so that a continuation or duplications of the loop 16, vertical portion 15, horizontal portion 14, together with a limb 12 and another loop 8 complete the rail engaging member. The limbs 12 and shanks 15 are in a plane parallel with the longitudinal vertical plane of one side of the bed, with the loops 17 straddling, to a slight extent, the rod 11. The portions 15 forming the shank may be brazed or secured together by any suitable means, a small strap 20 being shown to hold the two portions adjacent, the yoke formed below 80 being provided so that it may be carried around rods which are provided with ornamental sockets or trimmings at the junction of the vertical rods and the rail.

The clamp member 21 is formed preferably of two pieces of wire of the same character as that composing the rail engaging member, the loop 22 adapted to encircle the bed clothes and hold the same intermediate the loop 18 and loops 16, is provided with an eye 23 at one end and a hook 24 at the oppositely disposed end. An eye 25 formed in one end of the bar 26 engages with the eye 23 on the loop 22, the opposite end of the bar being provided with a hook 27 by which 95 it engages and hooks into the hook 24 previously described. The bar 26 is preferably provided with a hump 28, formed with a radius preferably the same as the rod 11, so that the movement thereon is limited to 100 some extent.

In the operation of the device, the rail engaging member is inserted from the inner side of the bed and the loops 8 forced over the lower rail, with the yoke straddling the rod 11, and the shank held engaged with the inner side of the rod which it straddles, the bed clothes are pulled down until a fold 30 is formed which falls between the loop 18 and loops 16. The clamp member is now 105 unhooked and brought with the loop 22 down in under the loop 18 and pulls the fold 110

30 closer in to the rod 11 and the hooks 24 and 27 are engaged, the tension depending to a great extent on the resiliency and adjustment of the bed clothes and the clothes 5 are securely clamped in contact with the rod and adjacent members.

A similar holder is inserted on the opposite side of the bed and the bed clothes secured, it having been found that the best position is about midway of the bed or where the clothes cover the body of an occupant. 10

What I claim is:

1. A bed clothes holder, comprising an integral bed rail engaging member having 15 an upper looped extension, and a separable clamp member, engaging and embracing said looped extension intermediate its looped extension and the opposite end.

2. In a bed clothes holder, in combination 20 with a bed rail and a rod on said rail, of an integral bed rail engaging member having an extension terminating in a plurality of loops formed of resilient material, a hinged clamp member, and means to secure said

clamp member in operative engagement between a pair of said loops and embracing said extension and said rod on said bed rail. 25

3. In a bed clothes holder, in combination with the side rail of a bed and a vertical rod secured therein, of an integral piece of wire, 30 formed with a plurality of loops and a depending shank, spread to form a yoke, the ends of said wire and yoke terminating in loops to engage said rail, and a hinged clamp member formed of wire provided with a hook and eye at its oppositely disposed ends, whereby said clamp can be engaged intermediate said first named loop and embrace said shank and rod to secure a 35 fold of bed clothes thereto. 40

In witness that I claim the foregoing I have hereunto subscribed my name this 21st day of January, 1913.

A. L. WORTHLEY.
